CHARGER FOR AUTOMATIC GUNS

Ernest W. Stacey, Beverly, and Augustus D. Willhauck, Stoneham, Mass., assignors to United Shoe Machinery Corporation, Flemington, N. J., a corporation of New Jersey

Application April 2, 1946, Serial No. 659,053

7 Claims. (Cl. 89—1)

1

This invention relates to ordnance and is illustrated as embodied in a charger for automatic guns.

In order to chamber a first cartridge in an automatic gun, such, for example, as a 37 mm. gun of the general type disclosed in United States Letters Patent No. 1,525,065, granted February 3, 1925, on an application filed in the name of John M. Browning, preparatory to the automatic firing of the gun, a crewman of the gun grasps an operating lever fulcrumed on and forming part of a lock frame of the gun and, after rotating the lever to lower a breech block of the gun from battery position, draws said lever, together with the lock frame, rearward until said lock frame has moved to recoil position in which it is temporarily held by a carrier dog of cartridge feeding mechanism housed in a feed box, various parts operative in a receiver of the gun then being arranged to receive a cartridge delivered by said cartridge feeding mechanism. A slide mounted on the top of the feed box and forming part of said cartridge feeding mechanism is then moved rearward by said crewman, causing a cartridge in a clip to be delivered to the feed box and then to the receiver, the cartridge as it passes through the feed box actuating suitable mechanism to cause the carrier dog to release the lock frame which, powered by spring assemblies and traveling in guideways in the receiver and an extension of the barrel, chambers the cartridge and moves the various gun parts back to battery position.

It is common practice manually to charge guns as above described, such action requiring considerable effort but being satisfactory provided there is space available properly to actuate the above-mentioned lock frame operating lever and the feed box slide. When guns such as above referred to are incorporated in turrets mounted in airplanes, however, they are often inaccessible and cannot be charged as above described.

With the foregoing considerations in view, it is an object of the present invention to provide a charger by the use of which a gunner operating an automatic gun of the 37 mm. type carried by a turret mounted in an airplane, for example, can quickly and effectively chamber the first cartridge in said gun or, in event that there is a misfire, extract a cartridge from the gun and chamber another cartridge in said gun. In accordance with a feature of the present invention there is provided, in combination with an automatic gun comprising a receiver, means for feeding a cartridge to the receiver, and means for chambering

5 a cartridge fed into the receiver; a movable actuating member, and mechanism movable in response to movement of said member for operating said cartridge chambering means and said cartridge feeding means in timed relation.

In the illustrative charger the actuating member constitutes a crank which is located in a position accessible to the gunner housed in a turret such as above referred to. The operating lever 10 of the lock frame of the gun is operated by an abutment pivotally mounted upon the rear end of a reciprocable rack which is operatively connected to said crank. As the crank is rotated in one direction the rack moves rearward in a rectilinear path, causing the operating lever to swing on the lock frame to move the breech block from its battery position to its retracted position and then causing the lock frame to be moved to recoil position in which it is held by the carrier dog of the feeding mechanism.

20 Associated with the rack is a yoke or coupling which, during rearward movement of the rack and under the influence of a spring, is permitted, by reason of movement of a lug carried by the rack, to be latched to a bifurcated lever operatively connected to said slide of the cartridge feeding mechanism. As the crank is rotated in an opposite direction the rack is returned forward to its rest position. During such movement the lug on the rack engages the yoke then latched to said bifurcated lever, causing the cartridge feeding mechanism to deliver a cartridge into the receiver of the gun and then to release the carrier dog of said mechanism to permit the lock frame, under the action of spring assemblies, to return the various gun parts, including the breech block, to their battery positions.

30 As the yoke is moved by the lug mounted upon the rack, it is released from the bifurcated lever connecting it to the cartridge feeding mechanism, 40 by an adjustable trip mechanism, with the result that the cartridge feeding mechanism is permitted to return to its rest position under spring action.

45 The above and other features, including safety devices for insuring that a cartridge shall be quickly and effectively chambered in the gun with a minimum amount of effort on the part of the gunner, will be understood and appreciated from the following detailed description read in connection with the accompanying drawings, in which

50 Fig. 1 is an angular view, partly broken away, of an automatic 37 mm. gun equipped with the illustrative charger, a lock frame of the gun having been moved to recoil position by the charger;

Fig. 2 is a side view, partly in section, of approximately the portion of the gun shown in Fig. 1, the various parts of the gun being in battery position and the charger being in its rest position;

Fig. 3 is a side view, partly broken away, showing the various parts of the gun at the time a cartridge is being transferred from a feed box to a receiver of the gun;

Fig. 4 shows a portion of the charger, partly broken away, as viewed on line IV—IV of Fig. 2;

Fig. 5 shows a portion of the charger, partly broken away, as viewed on line V—V of Fig. 2;

Fig. 6 shows a portion of the charger as viewed on line VI—VI of Fig. 4;

Fig. 7 is an angular view showing the feed box of the gun, portions of a loading handle cam assembly being shown swung aside from the feed box; and

Fig. 8 is a vertical section on line VIII—VIII of Fig. 2 showing cartridges assembled in a clip in the process of being delivered to the feed box of the gun.

In order initially to chamber a cartridge 20 (Figs. 3 and 8) in a barrel 24 (Figs. 2 and 3) of a 37 mm. gun 22 (Figs. 1, 2 and 3), or to extract a misfired cartridge, that is a cartridge which has failed to fire, from and to chamber another cartridge in said barrel, the gunner manually swings an operating lever 28, which is pivoted upon a pin 30 mounted upon a lock frame 32 of the gun, clockwise from its position shown in Fig. 2, causing a vertically slidable breech block 34 to be moved to its lowered or retracted position, shown in Fig. 3, against a stop 36. The lever 28 is then slid rearward, together with the lock frame 32, along guideways of a receiver 37 of the gun to a position just rearward of that shown in Figs. 1 and 3, the lever then being released and, accordingly, permitting the lock frame to slide forward slightly under the action of driving spring assemblies 38 until stopped by a carrier dog or latch 40 which is pivotally supported upon a carrier or cartridge depressor 42 pivoted upon a pin 44 secured to a feed box 46 housing cartridge feeding mechanism of the gun, the lock frame being provided with a notch 48 (Figs. 2 and 3) for receiving said dog. The carrier dog 40, when unaffected by the lock frame 32, is moved counterclockwise with relation to the carrier, as illustrated in Fig. 2, until a shoulder 50 (Fig. 2) thereof engages the carrier, by the action of a spring-pressed plunger 52 (Figs. 2, 3 and 7) housed in the carrier, the carrier dog being swung from its position shown in Fig. 2 to its position shown in Fig. 3 with relation to the then stationary carrier, against the action of the plunger, by the recoil action of the lock frame.

A clip 26 (Fig. 8) containing cartridges 20 is fed into the feed box 46 of the gun along ways 54 (Fig. 2) of said box by a slide 56 which is reciprocated by the action of recoiling parts of the gun upon a lever actuating arm 58 (Fig. 7), or which may be reciprocated for initially loading the gun, as will appear later, by the action of a cam 60 formed on a slide or loading handle cam assembly 62 movable longitudinally of the gun along guideways 64 (Figs. 1 and 8) of the feed box, on an upstanding stud 63 (Fig. 7) of the slide. The clip actuating slide 56 is provided with spring-pressed pawls 66 constructed and arranged to engage in openings 68 in the clips. Movement of the feed slide to its dash-dot position shown in Fig. 8, by reason of rearward movement of the slide 62 or the action of recoiling parts of the

gun upon the lever actuating arm 58, causes the clip 26 to be moved to the right, with the result that the leading cartridge 20 in the clip is cammed down out of the clip by tapered stripper cams 70, ready to be acted upon by the carrier 42 in a manner hereinafter described. During counter-recoil movement of the barrel 24 and a barrel extension 76 (Fig. 3) back to their battery positions, the feed slide 56 is moved from its dash-dot position shown in Fig. 8 to its full-line position, detents (not shown) serving to hold the clip against movement during retractive movement of the feed slide 56.

Lateral movement of the leading cartridge 20 being stripped from the clip 26 causes a carrier catch 72 (Figs. 2, 7 and 8), upon which the unsupported end of the carrier 42 rests, to be swung from beneath the carrier, with the result that the carrier, acted on by the spring-pressed plunger 52, depresses the cartridge stripped from the clip. When the carrier 42, depressing the stripped cartridge 20, has moved said cartridge to its dash-line position, shown in Fig. 3, into the receiver 37, the carrier dog 40 is moved out of the notch 48 of the lock frame 32, with the result that said frame is permitted to slide in counter-recoil under the action of the driving spring assemblies 38, thereby causing a rammer 74 (Fig. 3) of the lock frame, in cooperation with lands (not shown) of the barrel extension 76 in which the breech block 34 is vertically slidable, to move the cartridge into a chamber 78 (Fig. 3) of the barrel 24. When the operating lever 28, which may be said to constitute part of the lock frame 32, has reached the forward end of its counter-recoil movement, it is rotated counterclockwise, as viewed in Fig. 2, upon the pivot pin 30 to raise the breech block 34 back to battery position. During recoil movement of the lock frame 32 a hammer 80 (Fig. 3) carried by and slidable in the lock frame is cocked. After the cartridge has been chambered and the various parts of the gun have been moved to battery positions, the hammer is released by suitable mechanism (not shown) upon rearward movement of a trigger 82 (Figs. 2, 3 and 7), causing a firing pin 84 (Fig. 3) in the breech block 34 to fire the chambered cartridge. In the illustrative construction the trigger 82 is operated by a solenoid 86 (Fig. 1) controlled by a press button (not shown) mounted upon gun training controls positioned, for example, in a pressurized turret (not shown) to which a gun mount 88 is screwed to a trunnion block 90 of the gun is secured.

The illustrative charger comprises a rack or actuator 92 (Figs. 1, 2, 4 and 6) which is mounted for rectilinear movement in a guideway 94 formed in the gun mount 88, and a lengthwise adjustable rod 96 (Figs. 1, 2 and 8) which is pivotally connected at its rear end to the slide 62 and is pivotally connected at its forward end to a pin 98 (Figs. 1 and 2) carried by and forming part of a bifurcated lever 100 fulcrumed upon pivot pins 102 threaded into opposite sides of the gun mount 88. The rack 92 and the rod 96 are operated in succession, through mechanism herein-after described, to move the lock frame actuating lever 28 to its recoil position, for purposes above explained, and then to actuate the ammunition feed mechanism, commonly referred to as the ammunition feeder, of the gun in order to deliver a cartridge to the receiver 37 and thereafter to release the lock frame 32 so that it can move forward under the action of the

driving spring assemblies 38 to chamber the cartridge and to cause the various gun parts, then in positions in which they permit reception of a cartridge into the receiver, to be moved to battery position preparatory to firing the gun.

The rack 92 is operated by a gear 104 (Figs. 2, 4 and 6) keyed to a shaft 106 which is rotatably mounted in bearings of the gun mount 88 and has secured to its outer end a large gear 108 (Figs. 1, 2 and 5) meshing with a gear 110 (Fig. 2) secured to a shaft 112 also rotatably mounted in bearings of said mount and having secured to it a crank 114. As best shown in Fig. 4, a portion of the rack 92 is provided with a groove 116 (Figs. 1 and 4) which, after the rack has been moved away from its rest or forward position illustrated in Fig. 2, underlies and is slightly spaced from a spring-pressed detent 118 (Figs. 2, 4 and 6) housed in the gun mount 88, the central portions of the teeth of the rack arranged just forward of the groove 116 being in engagement with the detent when said rack is in its rest position, thereby insuring against displacement of the rack from its forward or rest position until it is desired to charge the gun.

Secured to the rear end of the rack 92 is a bracket 120 (Figs. 1, 2 and 5) having secured to it a pivot pin 122 (Fig. 2) supporting an abutment 124 which is U-shaped in cross section and is constantly urged into contact with a rear face 126 of the bracket by a spring 128 (Figs. 2 and 5) the forward end of which is attached to a pin forming part of the bracket and the rear end of which is attached to a pin forming part of the abutment. In order to cause the abutment 124 to be swung rearward with relation to the rack 92 to clear guide pins 130 (Figs. 1, 2 and 3) of the operating lever 28 during retraction of the rack and occasionally during rearward movement of the rack, as will appear later, a pair of cam plates 132 (Figs. 1 and 2) are secured to the opposite sides of the abutment.

Upon counterclockwise rotation of the crank 114, as viewed in Fig. 2, the rack 92 moves rearward, causing the abutment 124 to swing the operating lever 28 clockwise about the pivot pin 30 and to move the breech block 34 to its lowered position against the stop 36, further rearward movement of the rack 92 causing the lever and the lock frame 32 to be moved rearward as a unit along guideways of the receiver 31 back to recoil position, the carrier dog 40 dropping into the notch 48 in the upper surface of the lock frame to prevent forward or counter-recoil movement of said lock frame.

As above explained, after the lock frame 32 has been moved to its recoil position, shown in Fig. 3, the rod 96 is moved rearward, thereby operating ammunition feeding mechanism of the gun to deliver the first cartridge 20 of the clip 26 to the receiver 37, the lock frame then being released for forward or counter-recoil movement under the action of the driving spring assemblies 38 to cause chambering of the cartridge and the movement of the gun parts back to their battery positions.

The mechanism for operating the rod 96 in timed relation with the rack 92 will now be described. After the lock frame 32 has been moved rearward to recoil position, the crank 114 is rotated in a reverse direction, that is, clockwise, causing the rack 92 to move forward, a lug 134 (Figs. 1, 2 and 5) of the rack engaging a tie-rod 136 (Figs. 1 and 2) of a yoke or coupling 138 which is mounted for swinging

movement upon the pivot pins 102. The yoke 138 is constantly urged clockwise, as viewed in Figs. 1 and 2, by a spring 140 opposite ends of which are attached to the upper end of the yoke and to the gun mount 88, respectively.

The slide or loading handle cam assembly 62 is constantly urged forward by a spring 142 which is housed in a tube 144 secured to the cover of the feed box 46 and has its forward end engaging a boss 146 of the slide. Forward movement of the slide 62 with relation to the feed box 46 is limited by the engagement of the boss 146 with a nut 147 (Figs. 1 and 2) carried by a rod 148 which is secured at its rear end to the feed box and which passes through the spring 142 and through a bore 149 (Fig. 1) in said boss.

Mounted upon a pivot pin 152 (Figs. 1 and 2) carried by the lever 100 is a latch 154 which is normally forced against a surface 156 (Fig. 2) of the lever by a spring-pressed plunger 158 operating against the lower end of a vertically disposed portion of said latch. Secured to the gun mount 88 is a pedestal 160 provided with a trip rod 162 fitting in a rectilinear guideway 164 of the pedestal and having rotatably mounted in an extension thereof an adjustment screw 166 threaded into the pedestal, the trip rod being set in different adjusted positions lengthwise of the gun on the pedestal, for purposes which will appear later.

When the rack 92 is in its rest or forward position, the lug 134 secured to the rack has moved the yoke 138 to the position illustrated in Fig. 2 against the action of the spring 140. As the rack 92 is moved rearward, the yoke 138 operated by the spring 140 moves clockwise, as viewed in Fig. 2, as permitted by the lug 134 until a crossplate 168 of the yoke engages a flat surface 170 of the bifurcated lever 100, the upper portion of the plate during such movement engaging a bevel face 172 of the latch 154 and thus permitting the plate to swing forward of the hooked portion of the latch to the position shown in Fig. 1.

When the rack 92 is moved approximately three-quarters of the distance back to its forward or retracted position, the lug 134 engages the tie-rod 136 of the yoke 138 locked to the bifurcated lever 100, thereby swinging the yoke, together with the bifurcated lever, counterclockwise as viewed in Fig. 1, about the pivot pins 102 against the action of the springs 140, 142, with the result that the slide 62 is moved rearward along the guideways 64 of the feed box 46, the cam 60 (Fig. 7) of the slide operating upon the upstanding stud 63 of the feed slide 56 and, through mechanism above described, causing the first cartridge 20 of the clip 26 to be stripped from said clip and to be moved to the dash-dot position shown in Fig. 3. As the cartridge arrives at this position it knocks the carrier catch 72 from beneath the carrier 42, with the result that the carrier is released and, under the action of the spring-pressed plunger 52, moves the cartridge into its dash-line position shown in Fig. 3, into the receiver 37. As the cartridge 20 reaches this position in the receiver 37 the carrier dog 40 is moved out of the notch 48 of the lock frame 32, permitting said frame to move forward under the action of the spring assemblies 38 to chamber the cartridge, the operating lever then being swung counterclockwise, as viewed in Figs. 1 and 3, upon the lock frame to raise the breech block 34 back to battery position, the gun then being ready to be fired upon

70
75

actuation of the above-mentioned press button (not shown) which energizes the trigger operating solenoid 86.

When the slide 62 has moved rearward to an extent effectively to actuate the feed slide 56, as above explained, the vertically disposed portion of the latch 154 (Figs. 1 and 2) engages the rear end of the trip rod 162, with the result that the bifurcated lever 100 is released from the yoke 138 and, under the action of the springs 140, 142, the lever, together with the slide 62, is moved to its idle position, shown in Fig. 2. By this time the rack 92 will have moved forward to its retracted position, shown in Fig. 2, the spring-pressed detent 118 engaging portions of the rack teeth positioned just forward of the groove 116, thereby insuring against movement of the rack until it is again operated by turning the crank 114.

As the rack 92 is moved forward to its retracted position, the cams 132 engage the guide pin 130 of the operating lever 28, causing the abutment 124 to swing counterclockwise, as viewed in Figs. 2 and 3, against the action of the spring 128. It sometimes happens that the rack 92 is accidentally moved rearward after having moved the lock frame 32 to its recoil position. Should this happen, the abutment 124 will also be cammed down, so as to avoid striking the guide pin 130, by the action of the rear portions of the cams 132 against said pin.

In order to insure against the rack 92 being moved forward with considerable momentum under the action of the driving spring assemblies 38 should the gunner accidentally release the crank 114 (Fig. 1), for example, before moving the lock frame 32 to its recoil, latched-back position shown in Fig. 3, there is provided a pawl 174 or latch (Figs. 1, 2, 4 and 6) which is secured to a pin 176 journaled in the gun mount 88. A forward extension of the pawl 174 has attached to it the lower end of a spring 178, the upper end of said spring being attached to a lever 180 fulcrumed upon a pivot pin 182 secured to the gun mount. When the rearward end of the lever 180 is depressed by the tie-rod 136, the rack then being in its forward or retracted position, a shoulder 184 (Fig. 6) of the lever is moved away from an upstanding lug 186 (Figs. 1, 2 and 6) of the pawl, permitting the pawl to engage the teeth of the rack so as to stop forward movement of the rack in event that the crank 114 be accidentally released after partially moving the lock frame 32 back to recoil position.

As soon as the lock frame 32 has been moved rearward to a position in which it will be held in recoil position by the carrier dog 40 in event that the crank be released, laterally offset cams 188 (Figs. 4 and 6) carried by the rack lift the pawl 174, against the action of the spring 178, away from the teeth of the rack, causing the lug 186 of the pawl to move past the shoulder 184 of the lever 180, which then swings clockwise to the position shown in Fig. 6 into engagement with the shoulder. When the tie-rod 136 again depresses the rearward end of the lever 180 as the rack 92 reaches the forward end of its stroke, said lever is moved counterclockwise, thereby releasing the pawl 174 which then moves under the action of the spring 178 into engagement with the rack, as shown in Fig. 2.

Under some conditions, such, for example, as where there is a jamming of gun parts, it is desirable manually to release the pawl 174 so

that the rack 92 may be returned at any stage to its forward retracted position. Accordingly, the pin 176 to which the pawl 174 is secured has extending through it a handle 190 for swinging the pawl clockwise so that the lug 186 may be moved into engagement with the shoulder 184 into the position shown in Fig. 6.

In order to charge the gun, the gunner rotates the crank 114 counterclockwise as viewed in Fig. 2 causing rearward movement of the rack 92 and accordingly movement of the lock frame 32 to its recoil position. During rearward movement of the rack 92 the yoke 138 is attached to the bifurcated lever 100. The crank 114 is then rotated in an opposite direction to cause, through mechanism above described, rearward movement of the slide 62 and, accordingly, the chambering of the cartridge, the yoke 138 being disengaged from the bifurcated lever 100 before the rack 92 reaches its forward position thus enabling the various parts to assume their idle position illustrated in Fig. 2.

Having described our invention, what we claim as new and desire to secure by Letters Patent of the United States is:

1. In combination with an automatic gun provided with a receiver, a feeder for delivering cartridges to the receiver, a breech block, a lock frame movable from battery to recoil position to effect movement of the breech block away from battery position and to provide a space for delivery of a cartridge to the receiver, and means for temporarily holding the lock frame in recoil position; a charger comprising an actuator movable in one direction to move the lock frame from battery to recoil position in which it is temporarily held by said means, and connections which are associated with said actuator and said feeder and are movable in timed relation with said actuator for operating said feeder while the lock frame is in its recoil position to cause a cartridge to be fed to the receiver and to cause the releasing of the lock frame preparatory to chambering said cartridge.

2. In combination with an automatic gun comprising a receiver, a feed box, members reciprocable in the receiver from battery positions to recoil positions to provide in the receiver a space for receiving a cartridge from the feed box, and means for delivering a cartridge to the feed box and then into said space to a position to be operated upon by said members; a reciprocable actuator movable in one direction to move said members to recoil positions, and a coupling which is moved into latched relation with said means during movement of said actuator in said one direction and which is constructed and arranged to be engaged by said actuator to operate said means upon movement of said actuator in an opposite direction.

3. In combination with an automatic gun comprising a receiver, a feed box, a lock frame reciprocable in said receiver from a battery position to a recoil position to provide in the receiver a space for receiving a cartridge delivered from the feed box, and means for delivering a cartridge to said feed box and then into said space to a position to be operated upon by said lock frame; a manually operated reciprocable actuator movable in one direction to move said lock frame to recoil position, a coupling which is moved into latched relation with said cartridge delivering means upon movement of the actuator in said one direction and which is constructed and arranged to be operated by said actuator upon move-

76

ment of said actuator in an opposite direction, and trip means for causing said coupling to be disconnected from said means during movement of said actuator in said opposite direction.

4. In combination with an automatic gun comprising a barrel, a receiver, a spring assembly, a lock frame movable in said receiver to a recoil position against the action of the spring assembly, a latch for temporarily retaining said lock frame in recoil position, an operating lever pivotally mounted upon the lock frame, a breech block movable in response to movement of said lever, and a feeder for delivering cartridges to said receiver; a manually operative member, and means movable in one direction in response to movement of said member for causing said operating lever to move said breech block to a retracted position in which it allows access to a cartridge chamber of said barrel and for thereafter causing said lock frame and said lever to move against the action of said spring assemblies to recoil positions in which they are held temporarily by said latch, said means being movable in an opposite direction in response to movement of said member to cause operation of said feeder to deliver a cartridge to the receiver and for thereafter releasing the recoiled lock frame and operating lever, thereby permitting the lock frame and the operating lever to move under the action of said spring assemblies to battery position to chamber the cartridge and to move the breech block to battery position.

5. In combination with an automatic gun comprising a receiver, a feed box, means for delivering a cartridge to the feed box and then to the receiver, a spring assembly, and a member; an actuator movable in one direction from a rest position to move said member against the action of said spring assembly from a battery position to cause parts of the gun in the receiver to be moved into positions for the reception of a cartridge from the feed box, a coupling which is secured to said cartridge delivering means in response to movement of said actuator in said one direction and which is constructed and arranged to be operated by said actuator upon movement of said actuator in an opposite direction toward said rest position in order to operate said cartridge delivering means, a latch for preventing movement of said actuator toward said rest position after leaving said position until said actuator has moved a predetermined distance away from said rest position, a cam for rendering said latch ineffective after the actuator has moved said predetermined distance away from said rest position, and a ratchet for retaining said latch ineffective during movement of said actuator toward said rest position, said ratchet being movable in response to movement of the coupling just before said actuator arrives at its rest position to release the latch, thereby again rendering said latch effective.

6. In combination with an automatic gun comprising a receiver, feed mechanism for delivering cartridges to the receiver, a slide for delivering cartridges to said feed mechanism, a lock frame which comprises an operating lever and which is movable from a battery position to a recoil position to permit a cartridge to be moved into the receiver by said feed mechanism and is movable back to battery position to chamber said cartridge, and means associated with said feed mechanism for temporarily holding the lock frame in recoil position; actuating mechanism including a manually operated member arranged in an accessible

position, a reciprocable rack operatively connected to said member, and an abutment which is pivotally mounted upon the rack and is adapted upon movement of the rack in one direction to cause rotation and reciprocation of said lever to move the lock frame to its recoil position, a spring for constantly urging the abutment to a predetermined operative position with relation to the rack, a cam which is secured to the abutment and is shaped and arranged to move said abutment away from said operative position with relation to the rack during movement of said rack to insure against engagement of said abutment with portions of said lever when the lock frame is held temporarily in its recoil position and the rack is being reciprocated, and means for operatively connecting said slide and said rack, upon movement of the rack in a direction opposite to said one direction, in order to effect movement of said slide and thereby to cause said feed mechanism to deliver a cartridge to the receiver while the lock frame is held in recoil position.

7. In combination with an automatic gun comprising a feed box, a receiver, a slide for delivering cartridges to said feed box, and a lock frame which is movable from battery to recoil position to permit a cartridge to be delivered to the receiver from the feed box and which is movable back to battery position to cause said cartridge to be chambered; mechanism comprising a lever for operating said slide, resilient means for constantly urging said lever to an idle position, a manually operated member arranged in an accessible position, a reciprocatory actuator operatively connected to said member and constructed and arranged for movement in one direction to effect recoil movement of said lock frame, a yoke, a latch carried by said lever, a spring for constantly urging the yoke to a position in which it is secured to said lever by said latch, a lug secured to said actuator for moving the yoke against the action of said spring to an inoperative position, said lug being movable in said one direction together with the actuator to permit the yoke to be moved by said spring in latched relation with said lever and being movable in an opposite direction together with the actuator to actuate the yoke and accordingly said lever to operate said slide, thereby causing a cartridge to be delivered to the feed box and then to the receiver preparatory to chambering the cartridge upon counter-recoil movement of the lock frame, and means for operating the latch when said lever has been moved by the yoke a predetermined distance in said opposite direction to disconnect the lever from the yoke, thereby permitting the lever to move back to said idle position under the action of said resilient means.

60 ERNEST W. STACEY.

AUGUSTUS D. WILLHAUCK.
